CLAIM

The ornamental design for a cracker, as shown and
described.

DESCRIPTION

FIG. 1 is a perspective view of a cracker, embodying our
new design;

FIG. 2 is a back elevational view thereof;

FIG. 3 is a left side elevational view thereof;

FIG. 4 is a top planar view thereof;

FIG. 5 is a right side elevational view thereof;

FIG. 6 is a front elevational view thereof;

FIG. 7 is a perspective view of an alternative embodiment of
the cracker;

FIG. 8 is a back elevational view thereof;

FIG. 9 is a left side elevational view thereof;

FIG. 10 is a top planar view thereof;

FIG. 11 is a right side elevational view thereof;

FIG. 12 is a front elevational view thereof;

FIG. 13 is a perspective view of a further alternative
embodiment of the cracker;

FIG. 14 is a back elevational view thereof;

FIG. 15 is a left side elevational view thereof;

FIG. 16 is a top planar view thereof;

FIG. 17 is a right side elevational view thereof;

FIG. 18 is a front elevational view thereof;

FIG. 19 is a perspective view of a further alternative
embodiment of the cracker;

FIG. 20 is a back elevational view thereof;

FIG. 21 is a left side elevational view thereof;

FIG. 22 is a top planar view thereof;

FIG. 23 is a right side elevational view thereof; and,

FIG. 24 is a front elevational view thereof.

The broken line illustration of the center portion of the
sandwich-style cracker forms no part of the claimed design.
